(57) CLAIM

(21) Appl. No.: **29/136,606**

The ornamental design for a speedometer for bicycle, as shown.

(22) Filed: **Feb. 2, 2001**

DESCRIPTION

(30) Foreign Application Priority Data

Aug. 8, 2000 (JP) 12-021901

FIG. 1 is a front view of a speedometer for bicycle showing our new design;

(51) LOC (7) Cl. **10-04**

FIG. 2 is a rear view thereof;

(52) U.S. Cl. **D10/98**

FIG. 3 is a top plan thereof;

(58) Field of Search .... D10/98; 235/95 R, 235/95 A, 95 B, 95 C, 196, 197; 324/160-180

FIG. 4 is a bottom plan view thereof;

(56) References Cited

FIG. 5 is a right side view thereof; and,

U.S. PATENT DOCUMENTS

FIG. 6 is a perspective view thereof.
